UNITED STATES PATENT OFFICE

THOMAS F. CROCKER, OF CHICAGO, AND VICTOR S. THARP, OF ELMHURST, ILLINOIS,
ASSIGNORS, BY MESNE ASSIGNMENTS, TO ASSOCIATED ELECTRIC LABORATORIES,
INC., OF CHICAGO, ILLINOIS, A CORPORATION OF DELAWARE

TELEPHONE SYSTEM

Application filed December 18, 1930. Serial No. 503,164.

This invention relates to telephone systems in general, but is concerned more particularly with toll switching arrangements for handling toll or long-distance traffic in such systems. The object of the invention is the simplification of switchboards, switching apparatus and operating methods for enabling the toll operators to establish and supervise connections more efficiently than is possible with present equipment.

In present day practice, all toll switching for an exchange area is centralized at a toll switchboard. The switchboard ordinarily consists of inward, recording, and delay positions. The number of positions of each class will, of course, depend on the volume of traffic to be handled. Incoming calls from other exchange areas are answered by switching operators at the inward position and are either completed directly or transferred to a delay position for completion. Through calls, that is, calls in which the switchboard serves as a tandem switching point, are handled at the inward positions in much the same manner as incoming calls. In the case of outgoing toll calls, the calling subscriber will ordinarily call a special number to obtain a connection to a recording position. The recording operator will make out a ticket for the call and may either complete the call directly or pass the ticket to a delay position from which the call will be completed later.

The toll switchboard which comprises a part of the present invention includes the more or less standard position arrangement above described. Key controlled link circuits have been provided instead of the usual cord circuits for interconnecting lines and trunks. New and improved switching apparatus has also been provided for facilitating the establishment of connections.

One of the features of the invention is the arrangement for preventing the connection of a toll line with a trunk until the connection over the trunk line has been completed. This arrangement prevents the false operation of signals by the return of battery and ground from the switching apparatus employed in setting up a connection. Another feature is

the arrangement whereby an incoming call may be transferred to another position prior to answering by the operation of the release key of the link seized by the calling line. Another feature is the automatic ringing arrangement whereby on calls from certain positions ringing current is automatically applied to the called toll line or subscriber's line. Manually controlled reringing is also provided at these positions. A still further feature is the arrangement for indicating the group to which a calling line belongs. This is particularly advantageous in a system employing automatic call distribution as is the case in the present system. Another feature is the provision of a toll transmission selector which disconnects battery and ground from the trunk or the establishment of a connection with a subscriber's line whether idle or busy, or on finding all trunks in the called level busy. An incidental feature is the arrangement for connecting the impulse relay of the transmission selector to the supervisory conductor to give line seizure supervision. This circuit also serves to maintain the impulse relay operated until it is disconnected therefrom on the call being answered. This disconnecting of the impulse relay provides answering supervision. A still further feature is the ring-back switch for enabling a toll recording operator to recall a party line subscriber without releasing the original connection.

The foregoing features, together with others not specifically mentioned, will be discussed further in connection with the description of the operation of the invention, reference being had to the accompanying drawings comprising Figs. 1 to 13, inclusive. The drawings show, by means of the usual circuit diagrams, the essential equipment of a complete toll service switching system. Fig. 1 shows an operator's impulse sending device including a key set, control relays, and register-sender as provided for each position of the switchboard. Fig. 2 shows the telephone set and position apparatus as provided for each inward position. Fig. 3 shows a link circuit associated with the position apparatus of Fig. 2. In this figure there is also

shown an incoming toll line and its associated line-switch. Fig. 3A shows a link circuit associated with another inward position and a toll line with its associated lineswitch. Fig. 4 shows a toll selector associated with the link circuit of Fig. 3. Fig. 5 shows the telephone set and position apparatus as provided for each delay position. Fig. 6 shows a link circuit associated with the position apparatus of Fig. 5. Fig. 7 shows a toll transmission selector accessible to the various toll selectors. Fig. 8 shows a combination local and toll party line connector switch. Fig. 10 shows the telephone set and position apparatus as provided for each recording position. Fig. 11 shows a recording-completing link associated with the position apparatus of Fig. 10, a subscribers line and lineswitch, and a local selector. Fig. 12 shows a ring-back switch associated with the position apparatus of Fig. 10. Fig. 13 is a layout diagram showing how the various sheets of drawings should be arranged to be best understood.

Referring now to Fig. 1, key set KS is the usual type of key set comprising ten digit keys, a "Start" key and an "Error" key. Each time a key is operated the corresponding digit is set up in the register. An operator can thus record the number of a wanted line by operating the keys in accordance with the digits of the number. The register and associated sender shown in skeleton form, may be of any suitable type adapted to register and transmit numbers of five or more digits. A register-sender of the type disclosed in Patent No. 1,800,321, granted April 14, 1931, to N. H. Saunders et al., modified for the transmission of loop impulses is particularly suitable. Sufficient apparatus has been shown to indicate the modifications required in the sender disclosed in the above referred to application to adapt the same to transmit loop impulses. The modification consists principally of the addition of a second impulsive conductor which is connected to springs of the interrupter, start relay and stop relay in place of the ground connection shown in the application. A further modification consists of the use of the holding conductor for initiating the operation of the interrupter which is entirely satisfactory in this case. It will be noted that the designations applied to the relays and conductors of the register sender are the same as those used in the above application.

Reference to Fig. 13 will indicate that Fig. 1 is designed to cooperate with Figs. 2, 5, and 10. The various conductors connecting these figures have been designated accordingly.

In Fig. 2 is shown an operator's telephone set OT, position apparatus PA, and dial D. Each inward position is equipped in this manner. The position apparatus is permanently associated with a number of link circuits which are operatively connected thereto one

at a time by the operation of the answering keys of the link circuits. When a link circuit is connected to the position apparatus, the talking conductors of the link are looped through the apparatus with the telephone set connected in bridge. Ringing and splitting keys K1 and K2 such as are commonly used in toll cord circuits are provided. These keys are of the double throw type arranged to lock only when operated to splitting position. Release key K is a non-locking key for permitting the release of partially established connections without releasing the associated link. The position apparatus is normally associated with the register-sender apparatus of Fig. 1 through contacts of key K20. The dial D which is provided for use in case the register-sender fails to function properly may be connected up by operating key K20. The register-sender is operatively connected to the position apparatus on the operation of the "Start" key while the dial is connected responsive to its first movement from normal position. The operative connection of the calling device is maintained automatically until a connection is completed wherein the calling device is released. Dial pilot lamp L glows when the calling device is connected up in the above manner. The position apparatus is also arranged so that a ringing impulse is automatically sent out in all calls completed from the inward position. The ringing keys above referred to are therefore required only for re-ringing and for certain supervisory operations.

In Fig. 3 is shown a link circuit L associated with the position apparatus of Fig. 2. The link circuit is provided with a talking and monitoring key K3, a release key K4, a line lamp L2, a busy lamp L3 and a supervisory lamp L4. A selector (Fig. 4) is permanently and individually associated with the link. Link circuits such as L are accessible to lineswitches LS which terminate incoming toll lines. The trunks outgoing from the banks of the lineswitches will be distributed over the various inward positions, for example, the trunk from the fifth set of contacts extending to link L of one position, and the trunk from the sixth set of contacts extending to link L3 (Fig. 3A) of another position. It will be noted that in the bank level engaged by wiper 338, the odd numbered contacts are multiplied and connected to lamp L1 while the even numbered contacts are multiplied and connected to a corresponding lamp at a different position. Corresponding contacts of this bank level will be multiplied for the lineswitches of all toll lines of one group, that is, toll lines from the same exchange area. Each group of toll lines will be arranged in this manner and an identification lamp corresponding thereto will appear in each position. Lamp L19, incidentally, is a group lamp for the

group of toll lines including the line shown in Fig. 3A. It will be noted that the double wound ringing relay 301 is permanently bridged across the trunk in series with battery and ground. It may be noted, however, that the lower or battery connected winding is of extremely high resistance and is ineffective as far as operating the relay is concerned. The arrangement is provided for the purpose of keeping the negative line conductor "alive" which reduces faults due to dust accumulating on the relay contacts.

Fig. 3A shows a lineswitch LS2 and a link circuit L3 which are similar to corresponding apparatus shown in Fig. 3. The toll line terminating in lineswitch LS3 is assumed to be in a different group from the toll line shown in Fig. 3. The link circuit will connect with position apparatus such as that of Fig. 2 and will have its associated selector similar to selector S (Fig. 4).

In Fig. 4 is shown a toll selector S associated with the link circuit L of Fig. 3. This selector is of the well known Strowger vertical and rotary type provided with a fourth wiper for extending a supervisory circuit. The selector has access to toll lines, to transfer circuits at the delay positions, and to a toll switch train. For convenience of description, toll lines of the group including the toll line of Fig. 3A have been shown terminating in the fourth level of the selector banks. Toll service trunks have been shown terminating in the third level of the banks and transfer trunks terminating in the second level of the banks.

In Fig. 5 is shown an operator's telephone set OT1, position apparatus PA1 and dial D1 as provided for each delay position. This apparatus is similar to that of the inward position shown in Fig. 2 except that a calling device transfer key K7 and a coin control key K8 have been provided. The transfer key is necessitated by the double ended link circuits associated with this position. The control key is provided for controlling the collection and refund of coins in calls involving pay-station lines as it is assumed that calls of this class will be handled by a delay operator rather than by an inward operator. A further modification is the elimination of the automatic ringing feature which is considered undesirable at the delay position. Aside from points above noted, the equipment shown in this figure corresponds exactly with that shown in Fig. 3. The register-sender apparatus for this position will be the same as that shown in Fig. 1 and conductors extending thereto have been designated accordingly and so placed that they line up with corresponding conductors of Fig. 1 when that figure is placed to the left of Fig. 5.

Fig. 6 shows a double ended link circuit L1 and its associated selectors S1 and S2.

This link circuit is one of a number associated with each delay position (Fig. 5) and is used to set up tail-to-tail connections. The link circuit is provided with the usual talking and monitoring key K10, release key K11, recall lamp L9, supervisory lamp L10 and busy lamp L11. Selectors S1 and S2 are similar in all respects to selector S (Fig. 4) and have therefore been shown only in skeleton form. The banks of these selectors are multiplied with the banks of selector S on all levels except the second which is left vacant.

The toll transmission selector TTS shown in Fig. 7 is of the well known Strowger vertical and rotary type arranged to provide the transmission efficiency required in toll service. This selector is accessible to the toll selectors associated with the inward and delay positions and in turn has access to intermediate selectors or toll connectors, depending upon the size of the system. The selector is arranged to give both tone and flash busy supervision. Line seizure, answering, and disconnect supervision are given over a fourth conductor.

Fig. 8 shows a combination local and toll party-line connector which is accessible to toll transmission selectors such as selector TTS and to local selectors (not shown). The connector is arranged to feed battery to the calling and called subscribers and to ring automatically when used in local connections. When used in toll connections, the talking conductors are extended through to the called line without bridges or condensers and ringing is under control of the operator. The connector has access to party lines of which the line extending to substations T and T1 is shown. It will be understood, of course, that the system will include the usual individual line and rotary connectors in addition to the party line connector shown.

Fig. 9 shows a transfer link circuit over which calls transferred from the inward and recording positions are completed. This link circuit is associated with the position apparatus of Fig. 5. The link circuit is provided with the usual talking and monitoring key K12, release key K13, line lamp L12, supervisory lamp L13 and busy lamp L14. Selector S3 which is individual to the link L2 is identical with selector S (Fig. 4) and its banks are multiplied with the banks of selector S on all levels except the second.

In Fig. 10 is shown an operator's telephone set OT2, position apparatus PA2, and dial D2 for a recording position. This equipment is the same as that provided for the inward positions (Fig. 2) except that the automatic ringing feature has been eliminated and a calling device transfer key K16 has been provided. The conductors extending to the right-hand edge of the sheet

join with similarly designated conductors in Fig. 1.

In Fig. 11 there is shown a link circuit L4 which is accessible to subscribers over a first selector and toll-recording trunk. The link circuit is associated with the recording position apparatus of Fig. 10 and is provided with the usual talking and monitoring key K18, release key K19, supervisory lamp L16, busy lamp L17 and line lamp L18. Selector S4 associated with this link circuit is the same as selector S (Fig. 4), and its banks are multiplied with those of selector S on all levels except the third in which the toll service trunks are accessible. Substations T2 and T3 and the associated party line terminating in lineswitch LS1 are also shown in this figure. Selector S5 is an ordinary Strowger type selector accessible to lineswitches such as LS1 and having access to local trunks (not shown) and to toll recording trunks such as the trunk terminating in link L4.

The ring-back switch shown in Fig. 12 is associated with the recording position apparatus shown in Fig. 10 and has access by way of its banks to the toll recording trunks including the trunk shown in Fig. 11. The various trunks are identified by two digit code numbers. The switch is provided with an auxiliary ringing current selecting switch for selecting ringing current of the frequency required to signal a particular substation on a party line.

Having briefly described the apparatus comprising the invention, a detailed description of the operations involved in setting up various calls in a system employing the invention will now be given.

40 Incoming and through calls

Incoming and through calls are received and answered in the same manner and will be considered together. It will be assumed, by way of example, that an operator at a distant toll board has extended a connection over the toll line comprising conductors 391-392 which terminates in lineswitch LS. Ringing current applied to the toll line at the distant toll board energizes relay 302 which is bridged across the trunk conductors in series with condenser 350. Relay 302 is equipped with a mechanically locking armature which locks in operated position when the relay is energized and remains in this position until unlocked by relay 303. Relay 302 on operating completes a circuit for relay 305 by way of contacts 313 and 345. Relay 305 operates, completes a circuit at contacts 329 for switching relay 304 and stepping magnet 306 in series, and at contacts 328, connects test wiper 335 between the relay and the magnet. The contact engaged by wiper 335 in normal or "home" position is permanently connected to ground. This ground shunts

relay 304 and energizes magnet 306 which interrupts its own circuit at contacts 333. On releasing, magnet 306 advances the wipers one step and closes contacts 333. If the trunk terminating in this set of contacts is busy, the stepping operation is repeated. The wipers are thus moved ahead, step by step, until an idle trunk is found, whereon relay 304 is no longer shunted and operates to open the stepping circuit. It may be assumed that the trunk selected is the one comprising conductors 340-344 terminating in link L. Relay 304 on operating completes various circuits including the extension of the toll line conductors through to wipers 334 and 339 at contacts 316 and 326 respectively. The circuit of relay 305 is opened at contacts 345 and ground through contacts 313 is extended via contacts 320, resistance 387, wiper 337, conductor 342, contacts 362 and relay 353 to battery. Relay 303 is connected in parallel with relay 353 at contacts 346, but due to the value of resistance 387, relay 303 does not energize at this time. Relay 353 energizes over the above circuit and completes a circuit from ground through normally closed contacts of key K4 and contacts 368 for the lower winding of relay 354. Relay 353 also completes a circuit for lamp L2 at contacts 369 and the lamp glows to indicate an incoming call on link L. Relay 354 energizes, applies ground to conductor 341 at contacts 370 to hold relay 304 of the lineswitch operated, completes a locking circuit for its own lower winding at contacts 372 and completes a circuit for busy lamp L3 at contacts 373. Lamp L3 will remain lighted throughout the connection. The toll line will be marked busy in the banks of the toll selectors by ground via either contacts 330 or 347.

105 Transfer of incoming call

The operator may now answer the call, or if too busy, may transfer it to a different inward position for answering. The transfer is effected by momentarily operating key K4 to open the circuit of relay 354. Relay 354 on releasing opens the holding circuit of relay 304 which also releases. Relay 304 completes circuits for relay 305 and magnet 306 simultaneously, the latter circuit including wiper 336 and contacts 327 and 317. The magnet will operate as will relay 305 and the wipers will be advanced a step whereon the trunk engaged will be tested as previously described. The first idle trunk found will be seized. The call will thus be extended to a different position according to the bank multiplying arrangement in use. The call will operate the signal relays of the last seized link in exactly the same manner as described for link L.

120 Answering incoming call

To answer an incoming call on link L the

operator will operate key K3 to the left. A circuit is thereby established for the upper winding of relay 351 by way of contacts 389, conductor 215, and contacts 234. Relay 351 operates and completes a holding circuit for its lower winding by way of contacts 360, winding of relay 352, contacts 392, conductor 212, winding of relay 203, to ground. Relay 203 and relay 352 operate in series with the lower winding of relay 351 and effect various circuit changes which will be considered later. Relay 351 on operating opens the direct connection between the incoming and outgoing conductors of the link circuit, and loops them through the position equipment, the circuits being, respectively, conductor 340, contacts 357, conductor 223, contacts 235 and 237, conductor 222, contacts 359 to the upper talking conductor of the link circuit, and conductor 344, contacts 365, conductor 220, contacts 236 and 240, conductor 221, and contacts 364 to the lower talking conductor of the link circuit. Relay 351 also disconnects relay 353 from conductor 342 at contacts 362, and at contacts 361, connects direct ground to this conductor to energize relay 303 of the toll line. Relay 303 on operating unlocks relay 302 and opens the bridge across the trunk line at contacts 314. A circuit is closed for group lamp L1 at contacts 315, and the lamp glows to indicate the particular group of trunks from which the call originated. Relay 353 restores after its circuit is opened, opens the original energizing circuit of relay 354 at contacts 368, and opens the circuit of line lamp L2 at contacts 369. Relay 354 remains energized over its previously-traced locking circuit. Lamp L2 is extinguished at this time, but lamp L3 continues to glow to mark the trunk busy. As previously mentioned, relay 352 operates in series with relays 351 and 203. This relay prepares a holding circuit at contacts 367 for maintaining the relays energized in case key K3 is restored to normal before the calling operation has been completed. This latter circuit will be better appreciated when the operation of the register sender is considered later on. Relay 203 upon operating, as above mentioned, connects the operator's set across the talking conductors looped through the position equipment by way of contacts 230 and 231. The original energizing circuit of relay 351 is opened at contacts 234 and ground is applied to conductor 28 at contacts 228 to prepare the register to receive and record digits and to start the sender interrupter. The inward operator may now converse with the calling operator and obtain the necessary information regarding the connection desired.

Extension of through call

It will be assumed that the call is a through call to another exchange area served by toll lines such as the toll line comprising conductors 391'-392' shown in Fig. 3A, accessible in the fourth level of the toll selector banks. It will also be assumed that the register-sender (Fig. 1) is to be used in establishing the connection. The inward operator on receiving the necessary information actuates digit key 4 of the key set KS (Fig. 1) and the digit 4 will be recorded on the register. The operator will then actuate start key ST, thereby closing a circuit including contacts 20 for relay 11. Relay 11 on operating prepares a circuit for itself in series with relay 12 of contacts 17, and at contacts 15 and 16, respectively, connects ground to conductors 29 and 30. The operation of the register is such that as soon as the first digit is recorded, ground is connected to conductor 322, thereby energizing relay 13 of the relay group CR. Relay 13 prepares the sender-start circuit by closing contacts 22 and prepares a circuit for relay 12 at contacts 23. When the operator releases the start key, the original energizing circuit of relay 11 is opened and the short-circuit is removed from relay 12, thereby permitting this relay to energize in series with relay 11. Relay 12 on operating, closes the sender-start circuit at contacts 18, prepares a holding circuit at contacts 19, opens the original energizing circuit of relay 11 at contacts 20, and completes a circuit for relay 14 at contacts 21. Relay 14 energizes and transfers the holding circuit from conductor 28 to contacts 19 by way of contacts 25, thereby rendering the register-sender independent of ground from the operator's position equipment. Referring now to the position equipment, relay 208 energizes from ground via conductor 29 and contacts 266, short circuits relay 207 by closing contacts 253, connects an additional ground to conductor 30 at contacts 254, and at contacts 255 completes a circuit for relay 209. Relay 209 operates, closes a circuit for the dial pilot lamp L at contacts 242, prepares the automatic ringing circuit at contacts 256, and completes the previously-referred-to holding circuit for relays 203, 352, and 351 at contacts 257. Relays 205 and 206 operate initially from ground via conductor 30 and contacts 268. Relay 205 on operating opens the previously-traced loop through the position and extends the outgoing end by way of contacts 238-239, contacts 248 and 250, contacts 253, contacts 262 and 264, conductors 213' and 213, to the impulsing contacts of the sender. In the sender a loop circuit is completed through normally closed contacts of relay 502 so that at this time no impulses are transmitted even though interrupter I is operating continuously. Relay 206 in addition to closing points in the above control circuit, connects ground from the normally-closed contacts 258 of key K3, over contacts 249, conductor 216, contacts 388 and 366, upper winding of relay 354, lower winding of relay 355 to battery. Re-

lay 355 energizes and completes a locking circuit for its own upper winding by way of contacts 376 and 371, to ground on conductor 214. Relay 355 also extends the outgoing talking conductors of the link to selector S 5 by closing contacts 374 and 378, connects ground to holding conductor 381 at contacts 375 and connects supervisory relay 356 to conductor 382 at contacts 377. The control loop 10 previously traced to the sender from the position equipment now extends over conductors 380 and 383, contacts 411 and 418, upper and lower windings of relay 402, to battery and ground, respectively. Relay 402 energizes 15 and completes a circuit at contacts 419 for relay 403. Relay 403 energizes, prepares the impulsing circuit at contacts 422, and opens a point in the release circuit of contacts 423. The selector is now ready to receive impulses. 20 A short time after the operation of the "Start" key, that is, after an interval sufficient to permit the various relays to operate as described, relay 502 of the sender is energized to remove the short circuit from the 25 impulsing contacts of the sender interrupter I. The sender now transmits impulses over the loop until four impulses have been transmitted whereon the sender, under control of the register upon which this digit has been set 30 up, causes relay 503 to operate and again short circuit the impulsing contacts. Relay 502 restores and closes the original short circuit of the impulsing contacts and relay 503 restores in preparation for terminating the next series 35 of impulses. It will be seen, thus that the impulses are transmitted in a well-known manner according to the setting of the register, and that these impulses serve to operate the switch associated with the link circuit. 40 Referring now to selector S, relay 402 responds to the impulses in the usual way and transmits four impulses by way of contacts 420 and 422 to relay 404 and vertical magnet 406 in series. Relay 404 operates responsive 45 to the first impulse, and, due to its slow-releasing characteristics, remains operated throughout the series of impulses. The stepping magnet responds to each impulse and raises the wipers step by step to the called level. Off-normal contacts 424 and 427 close 50 on the first vertical step of the wipers, the latter contacts completing a circuit for relay 405 which operates and locks by way of interrupter contacts 430, contacts 429, and 416. 55 Shortly after the last impulse of the series, relay 404 restores and completes a circuit from ground on conductor 381, contacts 425 and 428 for rotary magnet 407. Magnet 407 energizes and steps the wipers in on the first 60 set of contacts of the called level and at the same time opens the locking circuit of relay 405 at contacts 430.

In case the first trunk of the group is busy, the test wiper of the selector will encounter 65 ground on the test contact and relay 405 will

operate from this ground over contacts 414, 430, and 427. Relay 405 will again complete a locking circuit for itself and close a circuit for magnet 407 which will energize to advance the wipers another step. The stepping 70 operation will be repeated as often as the test wiper encounters a grounded contact. When an idle trunk is encountered, for example, the trunk comprising conductors 384—386, the test wiper will find no ground and relay 75 401, no longer being shunted by ground on the test wiper, will operate in series with relay 405. The resistance of relay 401 is relatively high and relay 405 does not operate at this time. Relay 401 disconnects line relay 80 402 from conductors 380 and 383 at contacts 411 and 418, respectively, and extends these conductors by way of contacts 412 and 417 to the upper and lower wipers of the selector. Relay 401 also connects the test wiper to 85 grounded conductor 381 at contacts 415 for marking the seized trunk busy to other switches and for operating the cut-off relay of the toll line. A point in the release circuit is opened at contacts 416 so that, on the 90 restoration of relays 402 and 403, the release magnet cannot operate to restore the wiper to normal position. Assuming that the trunk selected is the one terminating in the toll line comprising conductors 391'—392' of Fig. 3A, 95 ground on the test wiper by way of conductor 384, and contacts 331' and 324' will operate relay 303' of the toll line. This relay will open the bridge including relay 302' which is normally connected across the trunk line, and thus prevent the operation of the associated 100 lineswitch when ringing current is sent over the toll line.

Referring now to the register-sender and position apparatus, it is to be noted that the 105 register is so arranged that ground is disconnected from conductor 322 when the registered digit or digits have been transmitted. Relay 13, consequently, releases, opens the sender starting circuit at contacts 22, and 110 opens the holding circuit of relays 11 and 12 at contacts 23. Relay 11 restores and disconnects ground from conductors 29 and 30. Relay 12 restores and opens the circuit of relay 14 which also restores. Relay 208, after a 115 short delay, releases responsive to the removal of ground from conductor 29. This relay opens the short circuit around relay 207 and opens a point in the circuit of relays 205 and 206. Relay 207 is thus momentarily 120 bridged across the talking conductors of the trunk, but does not operate due to the high resistances in series with relay 301' which is normally bridged across the trunk. Relays 205 and 206 restore due to the removal of 125 ground from conductor 30 and the opening of contacts 254. Relay 205 is provided with a copper slug on its core which makes the relay very slow to release. Relay 206 is provided with a noninductive winding which 130

slightly slows up the release of the relay which, however, will release ahead of relays 205 and 209. The purpose of the slow release feature of relay 206 will be explained in more detail in later paragraphs as it has 5 no utility in the present connection. During the interval after relay 206 restores and before relays 205 and 209 restore, a circuit is closed from battery, resistance 211, contacts 256, 247, and 238, conductor 222, contacts 359 10 and 374, conductor 380, contacts 412, upper wiper of selector S, conductor 386, upper winding of relay 301' (Fig. 3A) to ground. Relay 301' will operate momentarily and apply ringing current to the toll line at contacts 309' and 312'. Relays 205 and 209 will restore after a short interval as will relay 301' and the calling and toll line will be connected through the position apparatus. The ringing current applied to the called toll line 15 will operate the line signal at the distant toll board and an operator at that point will answer the call. The inward operator may now talk with either the calling or called operator alone by operating one or the other of keys 20 K1 or K2. The operation of key K1 to the left completes a circuit for relay 204 at contacts 241. Relay 204 disconnects the calling toll line from the operator's telephone set by opening contacts 235 and 236. The operation 25 of key K2 to the left completes a circuit for relay 205 at contacts 243 and this relay operates to disconnect the called toll line from the operator's telephone set by opening contacts 237 and 240.

On satisfying herself that the calling and called operators are properly connected, the inward operator will withdraw from the connection by restoring key K3 to normal. Upon 40 the restoration of key K3, the circuits for relay 351 and 352 will be opened since relay 209 at the position equipment has also restored, and these relays will deenergize followed by the release of relay 203. Relay 354 45 and relay 355, however, will remain energized over their previously-traced locking circuits and will maintain the connection through the selector as described. The calling toll line will now be extended through the link circuit and selector to the called toll line which 50 incidentally will be in normal condition with relay 301 restored. It will be noted that relay 351 upon restoring will disconnect the ground from the conductor 342, thereby permitting relay 303 of the calling toll line to 55 restore. The calling and called operators may now complete the connection to subscribers in the respective exchange areas.

Monitoring

60 After setting up a connection as above described, the inward operator may listen in at any time without interfering with the progress of the call. Key K3 is operated to the right, that is, to monitoring position and a

circuit is completed by way of contact 395, conductor 219, and contacts 233 for relay 202. Relay 202 connects the receiver across the secondary winding of induction coil IC at contacts 225 and 227. The primary winding 70 of the coil is normally bridged across conductors 217 and 218 in series with a condenser, and since key K3 is operated, the conductors are connected to the upper and lower talking conductors of the link via contacts 293 and 75 394, respectively. The inward operator cannot talk over the connection, however, since the transmitter of her telephone set is not connected up.

The monitoring key may also be employed 80 for answering calls when the sender is associated with one of the link circuits. Under these conditions, it will be recalled that relays 204 or 205 and relays 206, 208 and 209, or relays 206, 207, and 209 of the position apparatus 85 will be operated together with relays 351 and 352 of the link circuit. The answering key K3 of the link is then restored to normal and the relays are maintained over the auxiliary holding circuit previously 90 traced. If the monitoring key of another link circuit is now operated, the talking conductors of the link will now be extended to the position circuit to which the operator's telephone set is connected. Relays 351 and 352 95 of the second link will not be operated and the line lamp of the link will continue to glow. The inward operator may talk with the calling operator, however, since, as stated above, 100 the operator's telephone set (including transmitter) is connected to the position apparatus by relay 203 which is held up over the auxiliary circuit of the first link. When the sender completes its operation, the auxiliary circuit will be opened in the usual manner, 105 thus connecting the first toll line through to the called line. The operator's set will be disconnected by the release of relay 203, although of course it will still be in monitoring connection with the second toll line. The 110 operator will then operate the talking key of the second link and complete the connection as in the previous instance.

Recall

115 In case the inward operator desires to signal the operators at either of the distant toll boards involved in the above connection, this may be done by operating the proper ringing key at the position with key K3 operated. 120 The operation of key K1 to the right completes a circuit for relay 204 at contacts 264. Relay 204 disconnects the incoming branch of the link from the operators set and connects it through to the contacts of the ringing key. 125 A circuit may now be traced from battery, resistance 211, contacts 263 and 261, conductor 223, contacts 357, conductor 340, wiper 334, contacts 316, and upper winding of relay 301 to ground. Relay 301 will operate over 130

the above circuit and apply ringing current to the toll line at contacts 309 and 312. The operation of key K2 to the right will complete a circuit for relay 205 at contacts 245. 5 Relay 205 disconnects the outgoing branch of the link from the operator's set and connects it through to the contacts of the ringing key. A circuit for the ringing relay of the called toll line is completed from battery, resistance 211, contacts 244 and 238, conductor 222, contacts 359 and 374, conductor 380, contacts 412, upper wiper of selector S, conductor 386, upper winding of relay 301' to ground. Relay 301' will operate to apply ringing current 10 to the called toll line at contacts 309' and 312'.

Release

At the termination of the call, either operator may ring off in the usual way, thereby 20 operating relay 302 of the calling trunk line. This relay will again apply ground over contacts 313 and 320, wipers 337 of the lineswitch, conductor 342, and contacts 362 to relay 353. Relay 353 on operating will 25 complete a circuit for lamp L2 at contacts 369, and the lamp will glow to indicate that the operator is being called in on the connection. The inward operator will then 30 challenge the connection and, if no additional service is required, will restore the key K3 to normal and momentarily actuate key K4. The operation of key K4 opens the circuit 35 of relay 354 which restores and in turn opens the holding circuit of relay 355. Relay 355 releases and disconnects ground from holding conductor 381. The removal of ground from this conductor permits relay 401 of selector S to restore and close the circuit for 40 release magnet 408 at contacts 416. Magnet 408 operates to restore the switch wipers to normal position in a well known manner. The circuit for magnet 408 is opened at off-normal contacts 424 which open when the 45 wipers reach normal position.

All trunks busy

It was assumed in the foregoing case that an idle trunk in the fourth level was available when selector S was operated. If no 50 idle trunk had been available, the operation would be as follows: Referring back to the point at which the rotary stepping operation of selector S4 was described, it will be recalled that the wipers were stepped ahead 55 whenever a busy line was encountered. The wipers are thus rotated past the last set of contacts in the level whereupon the stepping operation ceases. The rotary cam springs operate in this position and ground from the 60 busy flash interrupter is connected to conductor 382 at contacts 410. This interrupted ground will cause relay 356 of the link circuit to operate intermittently and lamp L4 will consequently flash. A tone will be applied 65 simultaneously to the upper talking

conductor of the trunk by way of contacts 409, condenser 440 and contacts 412. This tone will be audible to the calling toll operator who is thus advised that no connection to the called toll line can be made at this 70 time. The inward operator may then release the connection as previously described.

Extension of an incoming call

The receipt and answering of an incoming 75 call was previously discussed. The extension of a call of this class is, in general, the same as the extension of a through call except that a toll service switch train is used to effect a connection with a subscriber's line. 80 By way of example, a call over the toll line comprising conductors 391-392 (Fig. 3) for the subscriber at substation T (Fig. 8) will be described. Since the operation of the register-sender (Fig. 1) has been discussed 85 previously, it will be assumed in this case that the connection is to be completed by means of the dial D. The number 4568 has been assigned arbitrarily to the called subscriber's line, and, since the trunks to the 90 group of toll transmission selectors including selector TTS (Fig. 7) are accessible in the third level of the banks of selector S (Fig. 4) it will be necessary for the operator to dial the number 34568 to reach the 95 wanted subscriber.

After answering the incoming call as previously described, the inward operator will operate key K20 thereby connecting up the dial D in place of the register sender. The 100 operator will then turn the dial to the position required for transmitting these impulses and the impulses will be sent out in the usual way as the dial returns to normal position. Off-normal contacts 270 and 271 close when 105 the dial is rotated from normal position and supply the ground for operating relays 205, 206, and 208. The operation is the same as that which results from the application of ground to conductors 29 and 30 by the register 110 sender control relays. A control circuit including impulse contacts 272 of the dial and contacts 263 and 265 of the transfer key, is extended through the position equipment and link to selector S as in the previously 115 described connection. Selector S operates in the usual manner and selects an idle trunk, for example, the trunk comprising conductors 435-438 which is accessible in the third level. When the selector switches through, the control circuit is further extended over the upper and lower wipers of the toll selector and conductors 435 and 438 the former conductor extending to ground via the lower left-hand winding of repeating coil RC, resistance 770 125 and contacts 723 to ground; the latter conductor extending via the upper left-hand winding of repeating coil RC, resistance 769, contacts 716, upper winding of impulse relay 707 and contacts 746 to battery. 130

When the calling device returns to normal, contacts 270 and 271 open whereupon relay 208 restores and opens the short circuit around relay 207. As previously stated, relay 207 is momentarily bridged across the control conductors before relays 206 and 207 release and in this case, relay 207 operates in series with relay 707 of selector TTS. Relay 207 completes a new circuit for relays 205 and 206 at contacts 251 and closes a circuit for relay 209 at contacts 252. The separation of the incoming and outgoing conductors of the link is thus maintained and battery and ground from the selector is kept off of the toll line so that no false signalling will result. Relay 209 maintains the holding circuit for relays 203, 351 and 352 and also the circuit for pilot lamp L.

It may be noted at this time that operations similar to the above take place when the register-sender is used and only a part of the called number transmitted. This permits the operator to complete the connection from this point by further operation of the register-sender or to release and establish the connection.

Referring now to selector TTS, relay 707 operates in series with relay 207 over the loop circuit above described. Relay 707 on operating completes a circuit for relay 708 which operates and prepares the usual impulsive circuit by closing contacts 748. The operator now dials the second digit of the number, i. e., the digit 4, and relay 707 responds accordingly. With each deenergization of relay 707 a circuit is closed from ground, contacts 744, 748, 751, winding of vertical magnet 713 to battery, and in parallel therewith, winding of relay 710 to battery. Relay 710 which is a slow-releasing relay maintains its operated position throughout the series of impulses and short circuits the upper left-hand winding of repeating coil RC at contacts 757 to improve the impulse transmission. The magnet responds to the impulses in the usual way and raises the wipers of the switch to the fourth level. Contacts 765, 767, and 781 close on the first vertical step of the wipers. Contacts 765 complete a circuit for relay 705 which operates and prepares a holding circuit for relay 706. Contacts 767 close a point in the circuit of release magnet 714, and contacts 781 close a point in the circuit of relay 711. Relay 711 now operates from ground on test conductor 437, contacts 742, 752, 759, winding of the relay, off-normal contacts 781, and contacts 746 to battery. Relay 711 on operating, completes a locking circuit for itself at contacts 760, this circuit including interrupter contacts 762 of the rotary magnet. The relay in addition closes a point in the circuit of the rotary magnet at contacts 761. Relay 710 restores shortly after the last impulse of the series and at contacts 758, completes the cir-

cuit for magnet 712. The magnet energizes and steps the wipers of the switch in on the first set of contacts of the called level, at the same time opening the circuit of relay 711 at contacts 762. In the event that the first trunk of the group is busy, the test wiper will encounter ground on the test contact, whereupon relay 711 will operate from this ground over contacts 754 and 762. Relay 711 will again complete the circuit for the rotary magnet which will again energize and advance the wipers another step. The stepping action will take place as long as the test wiper encounters grounded contacts. When an idle contact is found, for example, that associated with trunk line comprising conductors 774-777, there will be no ground on the test contacts and hence relay 711 will not operate. Relay 709, however, will no longer be shunted by ground on the test wiper and will operate from the ground on test conductor 437, contacts 742, winding of relay 709, contacts 762, winding of relay 711, off-normal contacts 781, and contacts 746 to battery. The resistance of relay 709 is relatively high and relay 711 does not operate in this circuit. Relay 709 on operating closes points in the control circuit to the switch ahead at contacts 749 and 755, close a point in the ring-control circuit, at contacts 750, disconnects the vertical magnet at contacts 751, and at contacts 753 connects the test wiper through to the incoming test conductor of the switch. Relay 709 also closes a circuit from ground, contacts 745, 782, 763, 717, upper winding of relay 701 to battery. Simultaneously with the closure of this circuit, a circuit is closed for the lower winding of relay 701 and impulse relay 803 of connector C in series. This circuit may be traced from battery through the upper winding of relay 803, contacts 827 and 817, conductor 774, upper wiper of selector TTS, contacts 743, 749, and 730, upper right-hand winding of repeating coil RC, contacts 719, lower winding of relay 701, lower right-hand winding of the repeating coil, contacts 734 and 755, lower wiper of the selector, conductor 777, contacts 825 and 829, lower winding of relay 803 to ground. Relay 803 operates over this circuit, but the direction of current flow is such that the two windings of relay 701 oppose each other and consequently that relay does not operate at this time.

The operator now dials the third digit of the number, that is, the digit 5, and relay 707 responds as in the previous instance. Relay 710 again operates during the transmission of impulses, but no stepping takes place since magnet 713 has been disconnected by the operation of relay 709. Relay 710 again short circuits the upper left-hand winding of repeating coil RC at contacts 757 to improve impulse transmission. Each time relay 707 deenergizes in response to an impulse, the previously-traced loop circuit

for relays 803 and 701 is opened at contacts 743, and relay 803 responds accordingly. The circuit of the upper winding of relay 701 is opened simultaneously at contacts 745 so that relay 701 remains unoperated during 5 the transmission of impulses. Referring now to the connector, relay 803 completes a circuit by way of contacts 823 and 832 for slow-to-release relay 804. Relay 804 operates and prepares various circuits among 10 which is the impulsive circuit including contacts 838. Relay 804 also prepares a circuit at contacts 836 by way of normally-closed off-normal contacts 890 for relay 807. Relay 807 operates and at contacts 859 connects 15 vertical magnet 812 to the impulsive circuit. Upon seizure of the connector, ground is extended by way of contacts 732, 750, control wiper, conductor 775, off-normal contacts 847, lower winding of relay 806 to battery. 20 Relay 806 operates and prepares a locking circuit for itself in series with the lower winding of relay 805. Relay 805, however, is now short-circuited by contacts until the 25 circuit around its lower winding is opened at contacts 890.

When relay 803 responds to the impulses repeated by relay 707 as previously described, a corresponding series of impulses is transmitted over the impulsive circuit which includes contacts 838, 864, 870, 888, and 859 to vertical magnet 812. The vertical magnet responds to the impulses and raises the shaft and wipers to the called level, in this case, the fifth level. Relay 810 is connected in 30 parallel with the vertical magnet and operates responsive to the first impulse and remains operated throughout the series of impulses. Off-normal contacts 847 and 890 35 open and off-normal contacts 834 close on the first vertical step of the wipers. The original energizing circuit of relay 807 is opened at contacts 890 on the first vertical step of the switch, but the relay remains energized 40 over the holding circuit including contacts 856 and 875, during the transmission of this series of impulses. The opening of contacts 847 removes the short circuit from the lower winding of relay 805, and this relay energizes 45 in series with the lower winding of relay 806. Relay 805 completes a locking circuit for its upper winding at contacts 845, separates the toll and local test conductors at contacts 843, and prepares various other 50 circuits which will be considered in detail hereinafter.

The operator now dials the fourth digit of the number, that is, the digit 6, and relays 707 and 803 respond as before. At this time 55 the impulses are transmitted to rotary magnet 813 since relay 807 deenergizes following the release of relay 810 and transfers the impulsive circuit to the magnet by way of contacts 860. Relay 810 again operates during 60 the series of impulses, and at contacts

872 prepares the busy test circuit. The rotary magnet responds to the impulses in the usual way and rotates the wipers of the switch around to the contacts of the called line, in this case assumed to be the called line 70 terminating in substation T.

Called line busy

In case the line is busy at this time, the test wiper will encounter ground on the test 75 contact and this ground, by way of contacts 872 and 882, will energize relay 809. Relay 809, on operating, prepares a locking circuit for itself at contacts 867, prepares a new locking circuit for relay 805 at contacts 869, 80 and at contacts 870 opens the impulsive circuit to prevent the switch from responding to additional impulses. In addition to the foregoing circuits, relay 809 completes a circuit which may be traced from the busy-flash 85 ground, contacts 841, 818, 899, 835, and 877, upper winding of relay 802 to battery. Relay 802 operates in this circuit and reverses the connection of line relay 803 to the trunk line by opening contacts 827 and 829 and 90 closing contacts 828 and 830. On the reversal of current flow, relay 701 of the transmission selector operates and completes a locking circuit for its upper winding at 95 contacts 718. The control loop to the connector is disconnected from the lower winding of relay 701 and extended through the upper and lower windings of relay 702 to battery and ground, respectively. The further results of the operation of relay 802 is 100 the closure of a circuit by way of contacts 826, 883, and 844 for relay 801. Relay 801 operates and locks to ground on conductor 776 by way of contacts 822 and 844, disconnects the trunk conductors from relay 803 at 105 contacts 817 and 825, and connects them through to the auxiliary talking conductors of the connector at contacts 819 and 824. Relay 801 connects an additional ground to local test conductor 779 at contacts 821 to 110 mark the trunk line busy to local connectors, and at contacts 823 opens a point in the release circuit to prevent the release of the connector at this time. The opening of contacts 818 disconnects relay 802 from the previously-traced circuit including the busy-flash interrupter, and the interrupter is connected over contacts 819, conductor 774, contacts 743, 749, and 730, upper right-hand winding of the repeating coil, contacts 720, 115 upper winding of relay 702 to battery. Relay 702 operates intermittently from the busy-flash ground and on each operation completes a circuit at contacts 725, relay 703. A further circuit closed on the operation of 120 relay 701 extends from battery, winding of relay 356 of the link circuit, contacts 377, conductor 382, contacts 413 and control wiper of selector S, conductor 436, contacts 724, lower winding of relay 706, contacts 729, 125

lower winding of relay 707, to ground. Relays 356 and 706 operate this circuit and relay 707 is maintained energized to hold up the connection. Relay 356 completes a circuit for supervisory lamp L4, contacts 379. 5 Relay 706, on operating, opens the circuit of relay 705 at contacts 738, prepares a holding circuit for itself at contacts 739 and 741 which is completed at contacts 736 on the release relay 705, and at contacts 740 shunts its own 10 lower winding. The short circuit of the lower winding of relay 706 makes this relay slow to release so that it remains operated until the holding circuit is closed by relay 705. 15 The supervisory circuit now includes only relay 356 and lower winding of relay 707.

As previously stated, relays 702 and 703 operate intermittently when the connector encounters a busy line. Relay 703, on operating, opens the previously-traced supervisory circuit at contacts 729, and at contacts 20 728 connects battery through resistance 772 to the lower winding of relay 707 to prevent the release of that relay. Relay 356 accordingly energizes and deenergizes intermittently, thus causing lamp L4 to flash and indicates to the operator that the subscriber's 25 line is busy at this time. The interrupted current in the right-hand winding of repeating coil RC will induce a tone in the left-hand windings which will be audible to the calling operator. Incidentally, the rate of interruption may be different from that used at the selectors, thus giving an indication of 30 the stage of the call at which the busy condition is encountered.

Referring now to the position apparatus, the disconnection of relay 707 from the control loop on the operation of relay 701 will 40 prevent relay 207 from operating when the calling device returns to normal and relays 205, 206, 208, and 209 will therefore restore and reestablish the loop through the position.

45 The operator will then release this connection by restoring key K3 of the link circuit and actuating key K4, whereon the conductors extending to the selector will be opened as described previously. The release of the toll switch train will be substantially the same as under the condition of a completed call, and will be described in detail in later paragraphs.

Called line idle

55 It was assumed in the above-described connection that the wanted line was busy when the connection was extended. In case the called line is idle, the operation will be the same as described up to the point where busy relay 809 was operated. When the line is 60 idle, the test wiper of the connector will find battery through the cut-off relay of the line switch and relay 809, consequently, will not operate under these conditions. When relay 65 810 restores shortly after the last impulse of

the series, the test wiper will be extended by way of contacts 871 to the upper winding of relay 811, and thence to ground by way of contacts 866, 861, and 837. Relay 811 will operate over this circuit and complete 70 a holding circuit for its lower winding at contacts 886, and at contacts 885 extend a holding ground through to the upper winding of relay 805. Relay 811 will also close points in the talking circuit of contacts 878 75 and 898, close a point in the ring-back tone circuit at contacts 879, complete a temporary holding circuit for relay 806 to contacts 880, connect direct ground to the test wiper at contacts 881, open a point in the circuit of 80 the busy test relay at contacts 882, and transfer the impulsing circuit from the rotary magnet of the connector to the stepping magnet of the auxiliary switch at contacts 887. 85 No supervision will be given at this time 85 since relay 801 is not operated. The operator will now dial the last digit of the number, that is, the digit 8, and relays 707 and 803 will respond as before. A corresponding series of impulses will be transmitted over 90 the impulsing circuit to operate magnet 815 of the auxiliary switch which will advance wipers 891 and 892 to the eighth set of contacts in the banks. Relay 810 will again operate 95 during the series of impulses, its only function, however being the opening of contacts 874. At the end of the series of impulses, relay 810 will restore and, since off-normal contacts 889 closed when the wipers of the auxiliary switch moved from normal position, a circuit will be closed from ground, 100 contacts 874 and 889, relay 808 to battery. When wiper 891 of the auxiliary switch passes the first half of its bank, a circuit is 105 closed for relay 807 which operates and reverses the ringing circuit with respect to the wipers. Relay 808, on operating, completes a circuit for relay 801 by way of contacts 844, 862, 885, and 836 to ground. Relay 801 110 operates and switches the connector over to talking position in the same manner as described for the operation of the relay on a call to a busy line. Impulse relay 803 is disconnected from the trunk and restores to 115 open the circuit of relay 804. This relay restores and closes various circuits including the release circuit which, however, is now open at contacts 823. Relay 811 is now held energized over a circuit including contacts 120 885, 862, and 822 to ground on test conductor 776. The talking conductors of the trunk are extended straight through to the wipers of the switch since ring-cut-off relay 806 is energized over control conductor 775. It 125 may be noted further that relay 801 in operating opens the temporary holding circuit of relay 806 at contacts 820 so that the operation of this relay is now entirely dependent upon the ground connection to the control conductor at the preceding switch. 130

Referring now to the transmission selector, the disconnection of relay 803 from the trunk line, opens the loop circuit over which the lower winding of relay 701 was energized to oppose the upper winding of that relay.

5 Under these conditions, relay 701 operates over its upper winding alone and completes a locking circuit for this winding to ground at off-normal contacts 765. Trunk conductors 435 and 438 are disconnected from relay 707 and ground and conductor 435 is extended by way of contacts 722 to relay 704. Supervisory conductor 436 is extended by way of contacts 724, lower winding of relay 706, contacts 729 to relay 707 and relay 706, together with supervisory relay 356 of the link circuit operate as previously described. Relay 707 is held energized over this circuit to prevent the release of the connection. Relay 706 performs the switching operation described in the previous call and relay 356 completes a circuit for lamp L4. Lamp L4 glows steadily to indicate to the operator that the wanted line has been seized. In the position circuit, 25 relays 206 and 208 will release followed shortly thereafter by relays 205 and 209. During the interval between the release of the two sets of relays a circuit will be completed from battery, resistance 211, contacts 256, 247, and 238, conductor 222, contacts 359 and 374, conductor 380, contacts 412, upper wiper of selector S, conductor 435, lower left-hand winding of repeating coil RC, resistance 770, contacts 722, relay 704 to ground. Relay 704 operates and disconnects ground from the ring control circuit at contacts 732, thereby releasing ring cut-off relay 806 of connector C. Relay 806, on restoring, completes the ringing circuit which may be traced from the 30 interrupter and generator, eighth contact engaged by wiper 892 of the auxiliary switch, contacts 863, 857, 848, and 878, upper wiper of the connector, over one side of the subscriber's line and through the substation 35 ringer, back over the other side of the line, lower wiper of the connector, contacts 898, 853, and 854, upper winding of relay 806 to battery. The subscriber is signalled intermittently by the ringing current which, in 40 this case, is of a frequency to which only the bell at the wanted substation responds. When the called subscriber answers, a direct current bridge is closed at the substation and relay 806 of the connector operates. Relay 806 disconnects the ringing current from the line and extends the line wipers through to the talking conductors of the switch. Relay 806 again locks to the control circuit. The subscriber's loop is thus extended through to 45 battery and ground through the windings of battery-feed relay 702 of the transmission selector and this relay operates. A circuit is closed at contacts 725 for relay 703 and this relay energizes and connects an additional ground to the ring control circuit of

contacts 727. A local holding circuit is completed for relay 707 at contacts 728, and at contacts 729 the circuit for supervisory relay 356 of the link circuit is opened. The supervisory relay restores and opens the circuit of 50 lamp L4 which is extinguished to indicate that the call has been answered. The inward operator will now withdraw from the connection restoring key K3 to normal. The connection, however, will still be maintained 75 since relay 354 is locked through contacts of key K3 and relay 355 is locked up through normally closed contacts of key K3.

At the end of the conversation, the called subscriber will restore his receiver 80 thus opening the loop circuit over which relay 702 was energized, and that relay will restore. Relay 703 will also restore and will reconnect the lower winding of relay 707 to the supervisory circuit, thereby reoperating relay 85 356 of the link circuit. Relay 356 will again close the circuit of lamp L4 which will glow to give disconnect supervision at the inward position.

Re-ring

90

The operator may re-ring the called subscriber by momentarily operating key K2 to the right. Battery through resistance 211 is connected up over contacts 244 and 238 to 95 the previously traced circuit for operating relay 704 of the transmission selector. Relay 704 will operate as before and open the circuit of relay 806 of the connector. This relay will release and complete the ringing circuit 100 previously described. The response of the called subscriber will effect the various switching operations described for the preceding call.

Release

105

When the called subscriber hangs up, supervisory lamp L4 glows as explained above and the inward operator, after challenging the line and getting no response, will signal the distant toll operator by applying ringing current to the toll line. This is done by actuating key K1 to the right, whereon a circuit is closed at contacts 264 for relay 204. Relay 204, on operating, disconnects the incoming talking conductors of the link from the operator's telephone set and extends these conductors by way of contacts 261 and 262 to contacts of ringing key K1. It will be recalled that relay 301 of the toll line is bridged 110 across the line conductors in series with ground and battery. This relay operates from battery through resistance 211 which is connected to the upper talking conductor 115 of the link and, at contacts 309 and 312, applies ringing current to the toll line. The ringing current will operate the signal at the distant toll board to inform the operator that the connection has terminated and should be released. The inward operator may wait on 120

125

120

125

130

the line and converse with the distant operator if desired.

After giving the distant operator the disconnect signal, the inward operator will proceed to release the switch train by restoring key K3 and operating key K4 momentarily.

5 Relay 354 will restore and open the circuit of relay 355 which will also restore and disconnect the outgoing conductors of the link circuit from the toll selector. The selector

10 S, transmission selector TTS, and connector C are held operated by ground on the test conductor as previously described, and when this conductor is opened at the link circuit,

15 the switches will restore to normal. In selector S, for example, removal of ground from conductor 381 will permit relay 401 to restore and close a circuit for magnet 408 at contacts 416. Magnet 408 will energize and

20 restore the wipers of the switch to normal in the usual way. Off-normal contacts 424 are opened when normal position is reached and interrupt the circuit of the release magnet.

The removal of ground from the test conductor and the opening of the control circuit will permit the release of relays 701, 706, 707, 708, and 709 of the transmission selector. Relays 707 and 708 on restoring will complete a circuit for release magnet 714 which operates to restore the wipers of the switch to normal position in the usual way. On the

30 wipers reaching the normal position, off-normal contacts 767 open the circuit of the release magnet.

35 In the connector switch, relays 801, 805, and 811 have been held operated over the test conductor and these relays will accordingly release when ground is removed from that conductor. Relay 806 has been held operated

40 over the control circuit and that relay will release when the control circuit is opened on the release of the transmission selector. Relay 807 has been held operated by ground on wiper 891 of the auxiliary switch, and relay

45 808 has been held operated over a circuit including off-normal contacts 889 of the auxiliary switch and these relays consequently will remain operated until the auxiliary switch has restored to normal, whereupon their cir-

50 cuits will be opened and they will release. The release of relay 801 will apply ground via contacts 823, 833, 839, 831, and off-normal contacts 834 to release magnet 814 and this magnet will operate in the usual way to re-

55 store the switch wipers to normal position. When the switch wipers on reaching normal position contacts 834 will operate to open the circuit of the release magnet. A parallel circuit is closed by way of contacts 865 for re-

60 lease magnet 816 of the auxiliary switch. Magnet 816 will operate to restore the wipers of the auxiliary switch to normal, and then when normal position is reached, relay 808 will restore, as previously stated, and open

65 the circuit of the magnet at contacts 865. The

various switches on releasing as set forth will remove the busy condition from the test contacts in the various switch banks and the switches will then be accessible to other calls.

All trunks busy

In the foregoing connections, it was assumed in each case that the various switches found idle trunks over which to extend the connection. Since this will not always be the case, special provisions have been made to signal the inward operator when any switch encounters an all-trunks-busy condition. Selector S, Fig. 4, for example, on failing to find an idle trunk will rotate to the eleventh position and signal the operator as previously described for through calls.

In case the toll-transmission selector (Fig. 7) fails to find an idle trunk, the wipers will be rotated to the eleventh position in the usual way, whereupon rotary off-normal contacts 764 and 768 will be closed and contacts 763 will be opened. It will be noted that in this case the switch is arranged for either tone or flash and tone busy. In case it is desired to use only the tone busy, the busy-tone machine will be connected up. In this case when the wipers reach the eleventh position, the loop circuit for the lower winding of relay 701 will be opened which permits this relay to operate and switch over the selector to talking position. Switching relay 709 will also operate as for a completed call and busy tone will be transmitted over rotary off-normal contacts

768, resistance 773, contacts 749 and 730, upper right-hand winding of repeating coil RC, contacts 720, and upper winding of relay 702 to battery. This tone will be induced in the left-hand winding of the repeating coil and will serve to notify the operator that no idle

trunk is available at this time. In case it is desired to use a flash busy signal, the busy-flash interrupter is connected up in place of the busy tone interrupter, and when relay

701 operates upon the switch stepping into the eleventh position, interrupted ground will be transmitted over the previously-traced circuit to the upper winding of relay 702 and that relay will operate intermittently. Relay 702 will accordingly close a circuit for

703 which will operate intermittently to open the supervisory circuit at contacts 729. Relay 356 of the link circuit will operate in a similar manner and will cause lamp L4 to flash in indication of the all-trunks-busy condition. The interrupted current in the right-hand winding of the repeating coil will induce a tone in the left-hand windings which tone will be audible to the calling operator.

Local calls

Referring now to connector C (Fig. 8), it will be noted that this connector is accessible to both local and toll selectors. When seized in a local call, test conductor 779 will function

and test and control conductors 775 and 776 will have no function to perform except that ground applied to conductor 775 will mark the switch busy in the banks of the toll transmission selectors. In local connections relay 805 consequently will not be operated and as a result relay 801 cannot operate. Relay 806 will not be energized on the seizure of the switch and will automatically apply ringing current to the called line as soon as the same is seized. Furthermore, in local connections, relay 803 will supply talking current to the calling subscriber and relay 802 will supply talking current to the called subscriber. Relay 802 will also reverse the direction of current flow over the calling line for metering and supervisory purposes. A detailed operation of the connector on local calls is not considered necessary since these operations are substantially the same as for standard party-line connectors which are well known in the art.

Incoming calls transferred to delay position

In some instances the inward operator may not find it convenient to complete calls in the manner described in preceding paragraphs. In this case, the calls may be transferred to the delay position and completed by the delay operator. An incoming call over the trunk line shown in Fig. 3, will be answered by the inward operator in exactly the same manner as in previously described calls. Instead of setting up the number of a toll line or a subscriber's line, the inward operator will register the number assigned to a trunk extending to the delay position, for example, a trunk line accessible on the second level on the banks of selector S (Fig. 4). Selector S will operate in the manner previously described to select a trunk line which for convenience will be assumed to be the trunk line comprising conductors 431—434 extending to the link circuit L2, Fig. 9. The selector will extend the connection over these trunk conductors of which conductors 431 and 434 are talking conductors, 432 is the supervisory conductor and 433 is the test conductor. Ground on test conductor 433 extends by way of contacts 924 and 926 to lamp L12 and the lamp glows to indicate a call on this link circuit. The supervisory conductor 432 extends by way of contacts 939 and 930 to ground, thereby operating relay 356 of the link circuit L. The lamp L4 glows to indicate that the connection has been extended to the delay position. The delay operator will answer this call by actuating key K12 to the left, thereby completing a circuit from ground, contacts 534, at the position apparatus (Fig. 5), conductor 515, contacts 907, upper winding of relay 902, upper winding of relay 903 to battery. Relays 902 and 903 operate, the former completing a holding circuit for the two relay 503' of the position

apparatus by way of contacts 919 and 908 and conductor 512. An auxiliary holding circuit is also prepared by way of contacts 920 and conductor 560. This auxiliary circuit corresponds to the auxiliary circuit described for the inward position and is for the purpose of maintaining relays 902 and 903 operated until the sender has completed its operation. Relay 902 separates the incoming talking conductors of the link from the outgoing talking conductors and loops them through the position apparatus. Conductor 431 extends by way of contacts 916, conductor 523, contacts 535 and 537, conductor 522, and contacts 917 to the upper talking conductor of the link circuit. Conductor 434 extends by way of contacts 923, conductor 520, contacts 536 and 540, conductor 521, and contacts 921 to the lower talking conductor of the link. The delay operator's telephone set is bridged across this loop at contacts 530 and 531, and the two operators may converse over the circuit including the two talking conductors of the trunk. Relay 903 on operating opens the circuit of lamp L12 at contacts 924, applies ground to test conductor 433 at contacts 925, and opens the supervisory circuit at contacts 939. Lamp L12 is extinguished as is lamp L4 at the inward position. Relay 503' of the position apparatus has the same functions as relay 203 of the inward position apparatus, that is, it bridges the operator's set across the loop to the position apparatus and connects ground to conductor 28 to prepare the register sender for operation.

The delay operator may now extend the connection over selector S3 to a toll line leading to another exchange area or to a subscriber's line by way of a toll switch train including a transmission selector such as selector TTS (Fig. 7) and connector C (Fig. 8). The operator of the register sender is the same as in the case of the inward operation. The delay operator registers the number wanted on the key set KS and depresses the start key. Ground is returned on conductors 29 and 30 to operate relays 505, 506, 508, and 509 of the position apparatus. The outgoing conductors of the link are transferred to the control circuit of the sender by relay 505. The circuit extends over contacts 539, 579, 585, 571, 550, and 595, conductor 213, through the impulsing contacts of the sender, conductor 213', contacts 593, 553, 548, 567, 583, 577 and 538. Relay 506 also completes a circuit from ground, contacts 570, 558, 549, and 573, conductor 516, contacts 906, lower winding of relay 905 of the link circuit, to battery. Relay 905 operates and locks by way of contacts 932, 911, and 909 to ground on conductor 514 during the time that key K12 is operated. On the restoration of this key, the locking circuit is transferred to ground by way of contacts 910. Relay 905 extends the talking conductors of the

link through to conductors 934 and 937 at contacts 929 and 938, thereby placing selector S3 under control of the register-sender. Ground is connected to test conductor 935 at contacts 942 and supervisory conductor 936 is extended to relay 904 by way of contacts 933. Busy lamp L14 glows to mark this trunk busy for the duration of a connection.

10 In the case of a call extending to another toll line, only selector S3 is operated and functions in the same manner as selector S (Fig. 4) in the previously-described call to a toll line. In calls to subscribers' lines a 15 transmission selector TTS, Fig. 7, and a connector C, Fig. 8, will be operated in the manner previously-described for the switches.

15 The sender on completing the transmission of the registered digits, causes ground to be removed from conductors 29 and 30, whereupon relay 508 restores followed by the restoration of relay 509. Relay 508 opens the short circuit around the winding of relay 507 at contacts 553, thereby momentarily connecting this relay across the loop extending to the switches. Relay 507 operates, however, when a connection has been only partially set up and completes a new holding circuit for relays 506 and 505 at contacts 551. 30 Relay 507 also completes a holding circuit for relay 509 at contacts 552 to maintain the relay operated and this relay in turn maintains the circuit of dial pilot lamp L5 at contacts 542. In a completed connection such 35 as described, relay 507 does not operate, hence, the calling device is disconnected from the loop and the calling and called lines connected through the position apparatus.

At this stage of the connection the delay 40 operator may either withdraw from the connection and place the ringing control with the inward operator or may control ringing by operating key K6 to the right. Assuming that the latter course is the one chosen, the 45 operation of this key completes a circuit for relay 505 which operates. Battery through resistance 511 is applied over contacts 544, 583, 577, and 538, conductor 522, contacts 917 and 929, conductor 934 to operate the ringing 50 relay of the trunk or the ring start relay of the transmission selector as the case may be. It will be noted, that the ringing in this connection is manually controlled.

55 The delay operator withdraws from the connection by restoring key K12 to normal, thereupon releasing relay 902. Relay 903 is now held over its lower winding and ground at contacts 941. The talking conductors of the link are extended back over 60 the previously-traced circuit to the link of the inward position, and in case the answering key of link L is still operated, the circuit includes the loop through the inward position. The inward operator's telephone set 65 is bridged across this loop so that the inward

operator may talk to either the calling or called party. When desired, the inward operator may also control ringing by operating key K2 (Fig. 2) to the right, thereby applying battery through resistance 211 to 70 the upper talking conductor of the link which extends, as previously described, through the delay position link L2, and selector S3 to the called toll line.

75 In the case of calls over the toll-service switch trains, supervision is given at the delay position by lamp L13 which lights when ground is returned over supervisory conductor 936. The delay operator may then release the connection by restoring key K12 80 to normal and by momentarily actuating key K13. All relays of the link circuit L2 will restore to normal, and ground by way of contacts 930 and 939 will be connected to supervisory conductor 432 to operate supervisory lamp L4 of the link circuit L at the inward position. The inward operator will then give disconnect supervision to the distant calling operator and will release the 85 remainder of the connection in the usual way. 90

95 It may be noted that the operator's position apparatus of Fig. 5 is, in general, the same as the apparatus of Fig. 2, except that in the delay position apparatus a two-way ringing key K7 has been provided, and a paystation coin-control key K8 has likewise been provided. The operating features aside from these involving the modifications above referred to are substantially the same as those of the inward position operator and 100 will not be described in detail.

Originating toll calls

105 The operation of the toll-recording position apparatus will now be considered. The apparatus for this position is shown in Figs. 10, 11, and 12. The operator's telephone set and position apparatus, Fig. 10, is substantially the same as that for the inward operator's position (Fig. 2), with the addition 110 of a recall key K16. This apparatus is designed and intended to operate with a register sender as shown in Fig. 1, which should be placed to the left of Fig. 10. It may be assumed, for example, that the subscriber 115 T2 desires to call a subscriber in a distant exchange system in which case the subscriber will dial the code number assigned for the toll-recording operator. Lineswitch LS1 will operate in the usual way responsive to the 120 initiation of the call and will seize an idle first selector, for example, the selector S5. Selector S5 will be operated in accordance with the code number dialled and will select an idle trunk incoming to the recording 125 position, which, for convenience, will be assumed to be the trunk extending to the link circuit L4. Relay 1104 will operate over the subscriber's loop to complete a circuit for relay 1102 at contacts 1123 and to com- 130

plete a circuit for line lamp L18 at contacts 1124. Relay 1102 on operating connects ring-back tone to the upper talking conductor of the trunk at contacts 1115 to inform the calling subscriber that the operator is being signalled. Ground is connected to the test conductor of the trunk by way of contacts 1151, 1161, and 1154 to hold up the switches of the local switch train. Lamp L18 glows to indicate an incoming call. Upon noting the lighted condition of the lamp, the recording operator will answer the call by actuating key K18 to the left. The holding circuit including the test conductor is transferred from contacts 1154 over contacts 1153 and conductor 1014 to ground at contacts 1059 of release key K17. A circuit is closed from ground at contacts 1034, conductor 1015, contacts 1160 upper winding of relay 1106, to battery. Relay 1106 operates and locks over its lower winding in series with relay 1107 by way of contacts 1130 and 1156, conductor 1012 and winding of relay 1003 to ground. Relays 1103 and 1107 also operate, the latter relay preparing a holding circuit by way of contacts 1136, conductor 1060, and also preparing a circuit for relay 1109 at contacts 1135. The incoming and outgoing talking conductors of the link circuit are opened and looped through the position equipment. The upper talking conductor extends by way of contacts 1127, conductor 1023, contacts 1035 and 1037, conductor 1022, contacts 1128 to the upper armature of relay 1109. The lower talking conductor of the link extends by way of contacts 1133, conductor 1020, contacts 1036, and 1040, conductor 1021 and contacts 1132 to the lower armature of relay 1109. The operator's set is bridged across the loop at the position equipment by the operation of relay 1003 and the operator may converse with the calling subscriber to determine his wants.

Originating toll calls may be completed either directly by the recording operator or indirectly by the delay operator. The present practice is to complete all calls directly when this is possible, and the present circuits are arranged with this operating feature in view. In either case, however, the recording operator will make out the usual ticket upon which are recorded the various data necessary for the proper billing of the call. In the case of a delayed call, this tick will be passed to the delay operator who will complete the call as will be explained hereinafter. Assuming that the call is one which the recording operator will complete directly, the operations involved are as follows: The recording operator sets up the code number necessary to select a particular group of trunks extending to the wanted exchange system. It may be assumed, for convenience, that the trunk line terminating in lineswitch LS2, Fig. 3A, is a trunk line in the group wanted. The record-

ing operator will accordingly depress the digit 4 key of the key set KS, thereby recording this digit on the register equipment. The "Start" key will then be operated to initiate the operation of the control apparatus (Fig. 1) which was previously described. Ground on conductors 29 and 30 as in previous connections will operate relays 1005, 1006, and 1008, and the latter relay will, in turn, complete a circuit to relay 1009. Relay 105 disconnects the incoming conductors of the link from the position loop and extends them to the control loop including the impulsing contacts of the sender switch. The circuits may be traced from conductor 1022, contacts 1038, 1048, 1053, and 1069 and 1079 to conductor 213', and from conductor 1021, contacts 1039, 1050, and 1067 and 1081 to conductor 213. Relay 1009 will complete the usual holding circuit for relays 1003, 1106, 1107, at contacts 1057 and complete a circuit for dial pilot lamp L15 at contacts 1065. Relay 1006 in addition to extending the control loop through in the usual manner at contacts 1048, 1050, at contacts 1049 completes an operating circuit for relay 1109 of the link. This relay operates and locks itself through contacts 1140 and contacts 1161 of release key K19. Busy lamp L17 of the link circuit glows to indicate busy condition of the trunk. Relay 1109 extends the talking conductors of the link circuit to selector S4 to place the selector under control of the register sender. Relay 1109 also completes a holding circuit for relay 1102 so that this relay will remain operated even though the calling subscriber hangs up and releases relay 1104. The sender will transmit the registered digit over the control loop in the usual manner to operate selector S4 to the level in which the trunk lines of the wanted ground are accessible. Selector S4 responds to the impulses transmitted by the sender and selects an idle trunk in the wanted group which will be assumed to be the trunk comprising conductors 384-386 which extends to the toll line shown in Fig. 3A. Ground on test conductors 384 operates cut-off relay 303' of the called toll line and the talking conductors of the trunk are connected with the talking conductors of the toll line. At the completion of the setting operation, relays 1005, 1006, and 1008, will have their circuits opened by the sender and will restore. Relay 1008 opens the short circuit around the winding of relay 1007 which does not operate, however, in a completed connection. The recording operator will now signal the distant operator by operating key K15 to the right. A circuit is closed for relay 1005 at contacts 1045 and 1046 this relay operates to switch the incoming conductors of the link over to the ringing key. Battery through resistance 1011 is applied over contacts 1044 and 1038, conductor 1022, contacts 1128 and 1138, conductor 1144, 130

upper wiper of selector S4, conductor 385, upper winding of relay 301 to ground. Relay 301 operates and connects ringing current to the toll line to signal the distant operator. The two operators now converse, the recording operator passing on the necessary information for completing the connection.

The recording operator may now withdraw from the connection by restoring key K18 to normal and the calling subscriber may now converse with the subscriber in the distant exchange.

At the termination of the call, the calling subscriber on hanging up will release relay 1104 which will complete a circuit by way of contacts 1125 and 1120 for the lamp L18. Lamp L18 will glow to indicate this condition to the recording operator. When the called subscriber at the distant exchange hangs up, the distant operator will receive the usual supervision and will apply ringing current to the trunk line. This ringing current over the toll line and interconnected trunk lines will operate relay 1105 of the recording link L4 which relay is bridged across the talking conductors of the link. Relay 1105 on operating will lock up mechanically and at contacts 1126 will close a circuit for supervisory lamp L16. The glowing of this lamp will give the recording operator the disconnect supervision. The connection may then be released by the momentary operation of key K19 which opens the circuit of relay 1109. Relay 1109 on restoring disconnects selector S4 at contacts 1138, 1139, 1141, and 1143, and opens the circuit of relay 1102 of contacts 1142. It will be noted that the connection from the calling subscriber to the recording position is maintained until released by the operator since relay 1102 will maintain the holding ground on the test conductor.

Recall

The recording operator will sometimes find it desirable to recall the subscriber that originated the call. Heretofore it has been the practice to reestablish a connection with the called subscriber by setting up an entirely new connection over the regular switch train. This has been necessary in party-line systems since under these conditions it is desirable to signal only the wanted subscriber and to do this, it is necessary to apply ringing current of a particularly frequency or code to the line which originated the call. In the present system, the calling subscriber may be recalled over the recording connection in the following manner. Without releasing the connection the recording operator will set up a code on the register sender of which the first two digits identify the recording trunk in use, and the last digit identify the particular subscriber who originated the call. It will be assumed, for example, that the recording trunk in use is arbitrarily designated by the digits 2 and 3, and that the subscriber to be recalled is at the party-line substation designated by the digit 4. The recording operator will accordingly set up the digits 2, 3, and 4 on the register and after actuating key K16 of her position apparatus, will depress the start key of the calling device in the usual way. The operation of key K16 disconnects conductor 30 which has no utility in the present connection, connects conductor 29 to lamp L15 so that this lamp will glow while the sender is in operation and disconnects impulse conductors 213' and 213 from the position apparatus and extends them by way of conductors 1073 and 1074 to the two windings of relay 1201 of connector RC (Fig. 12). Relay 1201 operates over the loop including the impulsing contacts of the sender and completes a circuit for relay 1202 at contacts 1222. Relay 1202 prepares various local holding circuits at contacts 1224 and 1225, prepares the impulsing circuit of contacts 1226, and opens a point in the circuit of the release magnet at contacts 1227. The sender now transmits the registered series of digits, that is, the digits 2, 3, and 4, and relay 1201 responds accordingly. In response to the first series of impulses, relay 1201 transmits impulses over circuits which initially include contacts 1223, 1226, 1218, winding of relay 1203, winding of vertical magnet 1209 to battery. Magnet 1209 operates and raises the wipers step by step to the called level. Relay 1203 operates in response to the first impulse and remains operated throughout the series of impulses. An impulsing circuit is completed by way of contacts 1217 and 1228 and the original circuit is opened at contacts 1218 when the off-normal springs operate on the first vertical step of the wipers. At the end of the first series of impulses, relay 1203 restores and transfers the impulsing circuit by way of contacts 1229, 1241, and 1251 to vertical magnet 1210. Relay 1210 responds in the same manner to the second series of impulses and transmits corresponding impulses over the impulsing circuit to operate rotary magnet 1210 which steps the wipers around to the contacts of the called recording trunk. Relay 1206 is connected in parallel with the rotary magnet and operates in response to the first impulse and, being a slow-to-release relay, remains operated throughout the series of impulses. At the end of the series of impulses, relay 1206 will restore and complete a circuit for relay 1207 which may be traced from battery, lower winding of cut-off relay 1101 of the link circuit, conductor 1149, test wiper of connector RC, contacts 1244, lower winding of relay 1207, contacts 1239 and 1224 to ground. Relay 1207 operates and locks to ground at contacts 1225 by way of contacts 1257, closes points in the ringing circuit at contacts 1249 and 1252, connects direct ground to the test wiper by way of contacts 130

1233 and 1248, and transfers the impulsing circuit from rotary magnet 1210 to stepping magnet 1214 of the auxiliary ringing-current selecting switch. Relay 1101 of the link circuit operates over the above circuit and 5 connects the incoming trunk conductors from the link and connects them instead to trunk conductors 1148 and 1150 extending to the ringing wipers of connector RC. Relay 1101 also applies a holding ground to the release 10 trunk conductor at contacts 1112 to hold up the connection from the calling line during the signalling operation.

The sender now transmits the third and 15 last digit of the code, that is, the digit 4 and relay 1201 responds and transmits a corresponding series of impulses to stepping magnet 1214 of the auxiliary switch. Relay 1206 again operates during the series of impulses and the stepping magnet advances the wipers 20 of the auxiliary switch to the fourth set of contacts of the bank. Shortly after the last impulse of the series, relay 1206 restores and a circuit is completed over wiper 1220 of the auxiliary switch and contacts 1246 for relay 25 1205. Relay 1205 operates, opens the impulsing circuit at contacts 1241, closes points in the ringing circuit at contacts 1240 and 1242, and closes a point in the release circuit at contacts 1243.

30 Ringing current is now applied to the line intermittently over a circuit extending from grounded generator or ground at the interrupter, wiper 1221 of the auxiliary switch, contacts 1237, 1242, 1252, and 1256, wiper 35 of the selector, conductor 1148, contacts 1111, bank contacts and wiper of selector S5, thence over one side of the calling line and through the bells and condenser at substation to the 40 other side of the calling line, wiper of the selector, and the bank contact engaged thereby, contacts 1113, conductor 1150, wiper of the connector, contacts 1253, 1249, 1240, and 1235, upper winding of ring-cut-off relay 45 1204, to battery. The bell rings at the substation corresponding to the signalling current sent out, that is, the substation designated by the digit 4. When the called subscriber answers, a direct current loop is closed 50 across the line conductors and relay 1204 of the connector operates. Relay 1204 on operating completes a locking circuit for its lower winding at contacts 1236, opens points in the ringing circuit at contacts 1235 and 55 1237, and opens the control circuit for relay 1201 at contacts 1231 and 1232. Relay 1201 accordingly deenergizes and opens the circuit of relay 1202 which also deenergizes. A 60 circuit is closed for the release magnet by way of contacts 1223, 1227 and off-normal contacts 1216. Relay 1202 completes a circuit at contacts 1230 for release magnet 1215 of the auxiliary and that switch is restored to normal. The auxiliary switch on reaching 65 normal position opens the circuit of relay

1205 which restores and in turn opens the circuit of release magnet 1215 at contacts 1243. When the switch wipers reach normal position, contacts 1216 interrupt the circuit of release magnet 1213, and contacts 1219 70 interrupt the circuit of relay 1204 which restores. Relay 1207 also restores following the release of relays 1202 and 1204. It may be noted that relay 1204 on operating disconnects ground from the test wiper of 75 the connector at contacts 1233, thereby opening the circuit of cut-off relay 1101 of the link circuit. Relay 1101 accordingly restores and again connects the incoming conductors to the talking conductors of the loop. Relay 1104 operates over the subscriber's loop 80 and again opens a circuit of lamp L18 at contacts 1125. In connection with this latter operation it is to be noted that relays 1102 and 1103 will be operated since, as stated, 85 the recall is made without releasing the connection previously established. The recording operator will now restore key K16 to normal and will establish a talking connection with the subscriber by operating key 90 K18 to the left.

It will be noted that the bank contacts of the bank engaged by wiper 1220 of the auxiliary switch are divided into two groups. It will be further noted that when the wiper 95 engages one of the first group of contacts, relay 1205 will be operated to initiate the ringing. When the wiper engages one of the last group of five contacts, relay 1208 will be energized in series with relay 1205 10 and will reverse the connection of the wipers to the ringing circuit by opening contacts 1253 and 1256 and closing contacts 1254 and 1255. This arrangement is provided so that full selective ten-party service may be given 10 on ten-party lines. In other words, digits 1 to 5, inclusive, select the five different frequencies of ringing current and apply them by way of the lower ringing wiper of the connector to one side of the line, while digits 6 to 10 select the same ringing frequencies, but apply them by way of the upper ringing wiper to the other side of the line.

Monitoring of connections of this type is substantially the same as for calls completed 11 from the inward position and will not be described in detail.

Delayed calls

In the case of delayed calls, the delay operator will first establish a connection with the calling subscriber, and when such connection has been established, will set up the connection to the wanted subscriber. Assume, for example, that the subscriber at substation T (Fig. 8) has requested a connection with a subscriber in a distant exchange reached over the trunk line terminating in lineswitch LS2 (Fig. 3A). The delay operator will select an idle link circuit, such as 11

the link circuit L1, and will operate the associated talking key K10 to the left. A circuit is completed for the upper winding of relay 602 via contacts 608, conductor 515 and contacts 534 to ground. Relay 602 on operating, 5 completes a locking circuit for its lower winding by way of contacts 618 and 609, conductor 512, winding of relay 503' to ground. An auxiliary holding circuit including contacts 619 and conductor 560 is prepared. This 10 circuit is later completed at contacts 557 to prevent the release of the link circuit during the operation of the sender in substantially the same manner as the auxiliary holding circuit described for the inward and recording 15 positions. Relay 602 also opens the direct connection between the incoming and outgoing branches of the link and connects them through the position apparatus. These circuits extend, respectively, from the upper 20 talking conductor of the branch of the link extending to selector S1, contacts 615, conductor 523, contacts 535 and 537, conductor 522, contacts 617, to the upper talking conductor of the branch extending to selector 25 S2, and from the lower talking conductor of the branch extending to selector S1, contacts 622, conductor 520, contacts 536 and 540, conductor 521, contacts 621 to the lower talking conductor of the branch extending to selector 30 S2. Relay 603 operates from ground at contacts 607, and this relay connects control conductors 588 and 589 to relay 654, and conductors 514 and 516 to relay 606.

The operator will now register the digits 35 of the subscriber's line on the key set KS and will operate the "Start" key to initiate the operation of the sender. Ground on conductor 29 will operate relay 508 and the ground on conductor 30 will operate relays 40 506 and 505. Relay 505 connects the conductors of the branch extending to selector S2 through to the impulse contacts of the sender over circuits extending, respectively, 45 via contacts 538, 577, 583, 567, 548, 553, and 593 to conductor 213'; and contacts 539, 579, 585, 571, 550, and 595 to conductors 213. Relay 506 in addition to closing the above-mentioned points in the impulsive circuit, close a 50 circuit from ground, contacts 570, 558, 549, 573, conductor 516, contacts 628, lower winding of relay 606, to battery. Relay 606 operates and locks over its upper winding by way of contacts 641, 627, conductor 514, and contacts 559 of release key K9 to ground. Relay 606 closes the talking conductors of the lower branch through to selector S2 over contacts 638 and 644, and conductors 649 and 652, connects ground at contacts 640 to holding conductor 650, and connects supervisory 55 relay 605 to supervisory conductor 651 and contacts 643. The sender now transmits the registered digits in the usual way and the digits serve to operate selector S2, toll-trans- 60 mision selector TTS and a connector such as

connector C, to extend the connection to the subscriber's line, and to select the proper ringing current to signal the subscriber. The operator, however, does not cause the connector to signal the subscriber at this time, 70 but operates key K7 to the left with the following results. Relay 504 is connected in series with relay 506 in place of relay 505 at contacts 568, but does not operate at this time since ground has been disconnected from conductors 29 and 30. The control loop of the sender is switched over at contacts 566 and 572 so that the next series of impulses will be transmitted over the upper branch of the link circuit. The operator will then register 80 the digits necessary for selecting a group of trunk lines to the distant exchange in which the wanted subscriber is located. This may be the digit 3 which will operate selector S1 to select an idle trunk such as the trunk line 85 terminating in lineswitch LS2 (Fig. 3A). The operation of the start key of the key set will initiate the sending operation in the manner previously described, relays 506, 504, 508, and 509 operating in the usual way. When 90 an idle toll line has been selected, the operator will restore key K7 to normal and will momentarily operate key K5 to the left, thereby closing a circuit for operating relay 504 at contacts 563 and applying battery through 95 resistance 511 to the upper talking conductor of the link by way of contacts 541 and 561. The battery connection, above referred to, operates the ringing relay of the selected trunk line in a manner previously described for signalling the operator at the distant exchange. 100 When the distant operator answers, the delay operator will pass the necessary information for setting up the connection in the distant exchange. When this connection has been completed and the wanted subscriber called, the delay operator will then signal the local subscriber by momentarily operating key K6 to the right. The operation of key K6 will complete a circuit for relay 505 which will 110 connect the lower branch of the link circuit to the ringing key. Battery will be connected by way of contacts 544, 583, 577, 538, conductor 522, contacts 617 and 638, conductor 649, wiper of the selector, trunk conductor 435 to the ringing relay of the transmission selector which incidentally may be the selector TTS (Fig. 7). The ringing relay will cause the connector to apply ringing current of the proper frequency to the called line to signal 115 the subscriber. When the subscriber's line is seized ground will be returned over the supervisory conductor in the usual manner, operating relay 605 of the link circuit. Relay 605 completes a circuit at contacts 630 for supervisory lamp L10. The ground is disconnected from conductor 651 when the subscriber answers and lamp L10 is extinguished. The operator may then withdraw 120 from the connection and allow the two sub- 130

scribers to carry on a conversation. The restoration of key K10 to normal will open a circuit to relays 602 and 603, whereupon these relays will restore. Relay 602 connects the two branches of the link circuit together directly and bridges relay 601 across the talking conductors. The original holding circuit for relays 654 and 606 will be opened by relay 603, but these relays will now be held energized from ground by way of contacts 653 of release key K11. Lamp L10 will glow when the first subscriber hangs up and ground is again applied to supervisory conductor 651. The distant operator will, of course, receive the usual disconnect supervision from the subscriber in that exchange, and will thereupon apply ringing current to the trunk line to give the delay operator the usual disconnect supervision. Relay 601 will respond to the ringing current on the trunk line. Relay 601, on operating, completes a circuit at contacts 613 for lamp L9 which will glow. The delay operator on noting the lighted condition of lamps L9 and L10 will release the connection by momentarily operating release key K11. The operation of key K11 opens the circuit for relays 654 and 606, and these relays restore and open the circuits to selectors S1 and S2, respectively. The switching apparatus releases under these conditions in the manner previously described. It may be noted that during the course of the connection the operator may talk with either party to the exclusion of the other by operating the respective splitting keys, that is, to talk with the subscriber reached over selector S1 and the upper branch of the link, key K5 is operated to the right, and to talk with the subscriber reached over selector S2 and the lower branch of the link, key K6 is operated to the left. Relays 504 and 505, respectively, respond and disconnect one or the other of the branches from the position circuit.

It will be further noted that the delay position circuit is arranged for paystation-coin control. Paystation lines when used will be accessible over a toll switch train adapted for this service. Switch trains of this type are well known and have not been shown in detail. In connections of this kind, the connection will be extended over selector S2 and the lower branch of the link circuit. By operating key K8 to the right or left, either negative or positive coin-control current will be applied to the lower talking conductor of the branch. The operation of the coin mechanism will be indicated by supervisory lamp L6 upon the operation of either of relays 510 or 513, as the case may be.

The release of the connection in this case is the same as on calls previously described.

An incidental feature of the various link circuits is the arrangement for marking them busy when an associated selector is busied locally for repairs or other purposes. Re-

ferring to link L (Fig. 3), it will be noted that test conductor 381 from selector S is connected through contacts 393 to test conductor 341 of the link. When selector S is busied, ground applied to the test conductor in the usual manner will mark link L busy to lineswitches such as LS. Link L1 is arranged somewhat differently. In this case test conductors 646 and 650 of selectors S1 and S2 are connected through contacts 632 and 639, respectively, to lamp L10. This lamp will light whenever either of the selectors is busied locally and will indicate this condition to the operator. In link circuit L2, the test conductor from selector S3 is connected through normally closed contacts 931 to relay 940. When the selector is made busy, relay 940 operates and connects ground to test conductor 433 to mark this link busy in the banks of the toll selectors. In link circuit L4, the test conductor 1145 from selector S4 is connected through normally closed contacts 1139 and 1116 to the test conductor of the associated recording trunk. When the selector is busied, ground from the selector applied over the above circuit will mark the trunk busy to local selectors such as selector S5.

What is claimed is:

1. In a telephone system, a toll switchboard, a toll line incoming to said switchboard, a hunting switch terminating the toll line and controlled thereover, a link circuit at the switchboard accessible to said hunting switch, a directly controlled switch individual to said link, and other toll lines and toll service trunk lines accessible to said second switch. 95
2. In a telephone system, a toll switchboard, a link circuit at the switchboard, an automatic switch individual to the link, toll lines terminating in non-numerical switches, means responsive to a call on one of said lines for operating the associated switch to connect the line with said link, a key in the link for answering the call, and means at the switchboard for operating said first switch to establish a connection via said link between the calling toll line and another toll line or a subscriber's line. 105
3. In a telephone system, a toll switchboard including two positions, link circuits at each position for extending connections, toll lines terminating in hunting switches having access to the link circuits at the first position, local subscriber controlled switches having access to the link circuits at the second position, and selector switches individual to the link circuits at each position and having access to said toll lines. 115
4. In a telephone system, a toll switchboard including two positions, link circuits at each position for extending connections, toll lines from other exchanges terminating in non-numerical switches having access to 130

- the link circuits at the first position, selector switches individual to the link circuits at the first position and having access to toll lines, to toll service trunks, and to the link circuits at the second position, and selector switches 5 individual to the link circuits at the second position having access to said toll lines and to said toll service trunks.
5. In a telephone system, a toll switch-board including three positions, link circuits 10 at the first position accessible to toll lines from other exchanges via non-numerical switches, a selector switch individual to each link circuit, link circuits at the second position accessible to local subscribers' lines via 15 a local switch train, a selector individual to each of the second said link circuits, link circuits at the third position accessible to the selectors associated with the link circuits at the first position, a selector individual to each of the third said link circuits, other link circuits at the third position for completing tail-to-tail connections, two selector switches individual to each of the other said link circuits, toll lines accessible to all of said selector 20 switches and toll service trunk lines accessible to the selectors associated with link circuits 25 at the first and third positions.
6. In a telephone system, a toll switch-board comprising three positions, link circuits 30 at the first position accessible to toll lines via non-numerical hunting switches, a selector switch individual to each of said links, link circuits at the second position accessible to calling subscribers via a local switch train, a selector switch individual to each of said second links, link circuits at the third position, two selector switches individual to each of said third links, toll lines 35 accessible to all of said selectors, and toll service trunk lines accessible to the selectors associated with links at the first and third 40 positions.
7. In a telephone system, toll lines incoming 45 from distant exchanges, means for extending calls over the toll lines from said exchanges, a local trunk line, operator controlled switching means for connecting said trunk line with subscribers' lines, and an operator's link circuit for connecting a calling toll line with said trunk line to establish a toll connection, said link circuit being individual to said trunk line and accessible via non-numerical hunting switches to all of said 55 toll lines.
8. In a telephone system, a plurality of link circuits for extending connections, a line, a hunting switch, means responsive to a call on the line for operating the switch to 60 connect the line with an idle one of said links, a key in said one link for answering the call, and a second key in said one link for causing said switch to connect the line with a different idle link provided said second key 65 is operated before said first key is operated.
9. In a telephone system, a plurality of link circuits for extending connections, a line, a hunting switch, means responsive to a call on the line for operating said switch to connect the line with an idle one of said links, 70 a key in said one link for answering the call and for adapting the link to further extend the call, and a second key in said one link for causing said switch to reoperate and connect said line with a different idle link provided said second key is operated first, and for releasing the connection provided said first key was previously operated and a connection extended over the link. 75
10. In a telephone system, a cordless toll switchboard comprising common position apparatus including a ringing key and a calling device and a plurality of link circuits, a key in each link for temporarily associating the link with said apparatus, means including the calling device for extending a connection over a link to a called line, signalling means for applying ringing current to the called line, means in said position apparatus for automatically operating said signalling 80 means responsive to the completion of the connection, and means including said ringing key for reoperating said signalling means. 85
11. In a telephone system, a cordless toll switchboard comprising common position apparatus including a ringing key and a calling device and a plurality of link circuits, a key in each link for temporarily associating the link with said apparatus, means including the calling device for extending a connection to a called line, a relay for applying ringing current to the line, automatic means in the position apparatus for momentarily operating said relay responsive to 90 the completion of the connection, and means including said ringing key for reoperating said relay at will. 95
12. In a telephone system, a cordless toll switchboard comprising common position apparatus including a ringing key and a calling device and a plurality of link circuits a key in each link for temporarily associating the link with said apparatus, means including the calling device for extending a connection over a link and a train of automatic switches to a subscriber's line, means in the last switch of the train for applying ringing current to the subscriber's line, means in the 100 position apparatus automatically responsive to the completion of the connection for initiating the operation of said ringing means, means for disabling said ringing means responsive to the answering of the call, and means including said ringing key for initiating the reoperation of said ringing means after the called subscriber has withdrawn from the connection. 110
13. In a telephone system in which calls are extended over a train of automatic switches 105 115 120 125 130

by means of a loop control circuit and in which the completion of a connection is marked by the absence of ground and battery connections to the distant end of the circuit, a calling device for interrupting the circuit 5 in accordance with the digits of a wanted number to control the establishment of the connection, and means for momentarily connecting a relay across said circuit in place of said calling device after each digit dialled 10 to determine whether or not the connection has been completed.

14. In a telephone system in which calls are extended over a train of automatic switches by means of a loop control circuit 15 and in which the completion of a connection is marked by the absence of battery and ground connections to the distant end of the circuit, an impulse sender and means for connecting it in said circuit, a register for controlling the operation of said sender in transmitting impulses representing digits of a called number over said circuit to control the establishment of a connection, and means for momentarily connecting a relay across said 20 circuit at the completion of the operation of the sender to test said circuit for battery and ground connections.

15. In a telephone system, a toll line, automatic switches, a link circuit comprising two 30 normally connected sections, means for connecting said line with one section of the link, a calling device and means for connecting it to the other section of the link, means responsive to the connection of the calling device to said other section of the link for opening the normal connection between said sections and for connecting said other section with one of said switches, means including the calling device 35 for operating said switches to extend a connection in the direction of a called line, means for preventing the reconnection of said two sections of the link during the operation of the calling device, and means for preventing the reconnection of said two sections of the link at the completion of the operation of the calling device provided no connection has been established to the called line.

16. In a telephone system, a toll line, a train 50 of automatic switches, a link circuit comprising two normally connected sections, means for connecting said line with one section of the link, a calling device, means responsive to the initiation of the operation of the calling device for connecting the same with the other section of the link, for connecting said other section to the first switch of the train, and for opening the normal connection between said two sections, means including the calling 55 device for transmitting digit impulses to operate successive switches of the train to extend a connection in the direction of a called line, means for preventing the reconnection of said two sections during the operation of the calling device, and means for preventing 60

the reconnection of said two sections at the completion of the operation of the calling device in case insufficient digits have been transmitted to operate each switch in said train.

17. In a telephone system, a manual switchboard, a link circuit, a plurality of groups of lines, a signal at the switchboard for said link, a signal at the switchboard for each of said groups of lines, means responsive to a call over any one of said lines for connecting the line with said link, means responsive to the connection of the line with the link for operating said first signal, means for answering the call, and means responsive to the answering of the call for operating a particular one of said second signals corresponding to the group to which the calling line belongs.

18. In a telephone system, a plurality of link circuits individual to an operator's position, a plurality of groups of incoming toll lines, a signal at the position for each of said links, a signal at the position for each of said groups of lines, means responsive to a call over any one of said lines for connecting the line with an idle one of said links, means responsive to such connection for operating the signal corresponding to the connected link, means in the link for answering the call, and means responsive to the answering of the call for operating the signal corresponding to the group of lines to which the calling line belongs.

19. In a telephone system, an automatic switch, a trunk line comprising two talking conductors, a holding conductor and a supervisory conductor terminating in the switch, a double wound relay in the switch for controlling the operation of the switch to extend a connection to a called line, an operating circuit for said relay including one winding thereof and said two talking conductors in series completed responsive to the seizure of the trunk line, and a holding circuit for said relay including the other winding thereof and said supervisory conductor completed responsive to the establishment of the connection with the called line.

20. In a telephone system, an automatic switch, a trunk line comprising two talking conductors, a holding conductor and a supervisory conductor terminating in the switch, a double wound relay in the switch for controlling the operation of the switch to extend a connection to a called line means for completing an operating circuit including one winding of the relay and said talking conductors in series responsive to the seizure of the trunk line, and means for disconnecting said relay from said operating circuit and for completing a holding circuit including the other winding of the relay and said supervisory conductor responsive to the establishment of the connection with the called line.

21. In a telephone system, an automatic

switch, a trunk line including three conductors terminating in said switch, a double wound relay in the switch for controlling the operation thereof to extend a connection to a called line, means for completing an operating circuit including one winding of the relay and two conductors of the trunk line in series responsive to the seizure of the trunk line, means for disconnecting the relay from said circuit and for completing a holding circuit including the other winding of the relay and the third conductor of the trunk line responsive to the establishment of the connection with the called line, and a supervisory signal associated with the trunk line operated responsive to the establishment of said holding circuit.

22. In a telephone system, an automatic switch, a trunk line including three conductors terminating in said switch, a double wound relay for controlling the operation of the switch to extend a call to a subscriber's line, an operating circuit for said relay including one winding of the relay and two conductors of the trunk line in series, means for disconnecting the relay from said operating circuit and for completing a holding circuit including the other winding of the relay and the third conductor of the trunk line responsive to the extension of the call to the subscriber's line, means for disconnecting the relay from said holding circuit and for establishing a local holding circuit including said other winding of the relay responsive to the answering of the call, and means for reestablishing said first holding circuit responsive to the called subscriber terminating the call.

23. In a telephone system, an automatic switch, a trunk line including three conductors terminating in said switch, a double wound impulse relay in the switch for controlling the operation thereof to extend a call to a subscriber's line, an operating circuit for the relay including one of said windings and two conductors of the trunk line in series, means for disconnecting the relay from said operating circuit and for completing a holding circuit including the other winding of the relay and the third conductor of the trunk line responsive to the extension of the call to the subscriber's line, and means for disconnecting the relay from said third conductor and for establishing a local holding circuit including said other winding responsive to the answering of the call.

24. In a telephone system, a party line, a trunk line extending to an operator's position, subscriber controlled means for extending a connection from said party line to said trunk line, means for maintaining the connection after the calling subscriber hangs up, and a directly controlled switch for selecting and applying ringing current to the connection to selectively signal the particular subscriber who originated the call.

25. In a telephone system, a party line, an operator's position, a trunk line terminating in a link circuit at the position, subscriber controlled means for establishing a connection from said party line to said link via 70 said trunk line, means for preventing the release of the connection when the calling subscriber hangs up, a switching device, means at the position for operating said device to connect with said trunk line, and means in 75 said device for disconnecting the trunk line from said link and for selectively signalling the subscriber who originally established the connection.

26. In a telephone system, a party line, an operator's position, a trunk line terminating in a link circuit at the position, subscriber controlled means for establishing a connection from said party line to said link via 80 said trunk line, means for preventing the release of the connection when the calling subscriber hangs up, an operator controlled automatic switch for establishing a connection with the trunk line engaged in said connection, means in said switch for disconnecting 85 the trunk line from the link and for applying ringing current thereto to selectively signal the subscriber who established the connection, and means responsive to the subscriber answering the signal for releasing 90 said switch and for reconnecting the trunk line to said link.

27. In a telephone system, a temporarily established connection between a party line and an operator's link circuit, means including a directly operated switch for extending a branch connection to said first connection, means responsive to the establishment of the branch connection for opening the connection to said link, means in the switch 100 for applying ringing current to the called line over said branch connection to selectively signal a particular station on said line, and means controlled over the line for releasing said switch and for reestablishing the 105 connection with said link.

28. In a telephone system, a trunk line, automatic switches, a link circuit connected to the trunk line, means controlled over the trunk line from said link for directly operating said switches to extend a connection to a called line, signalling means in one of said switches for applying ringing current to the called line, a source of direct current, and means associated with said link 110 for momentarily connecting said current source to one conductor of the trunk line to initiate the operation of said signalling means.

29. In a telephone system, a trunk line, automatic switches, a link circuit connected to the trunk line, means controlled over the trunk line for operating said switches to extend a call to a line, signalling means in one of said switches for applying ringing 115 current to the called line, a source of direct current, and means associated with said link 120 for momentarily connecting said current source to one conductor of the trunk line to initiate the operation of said signalling means.

current to the line, a source of direct current, means associated with the link for momentarily connecting said current source to a conductor of the trunk line to initiate the operation of said signalling means,
6 means controlled over the called line for disabling said signalling means, and manually controlled means associated with the link circuit for reconnecting said current source to a conductor of the trunk line to initiate the
10 reoperation of said signalling means.

30. In a telephone system, party lines, trunk lines terminating at an operator's position, automatic switches for extending connections from said party lines to said trunk lines, means at the position for further extending the connections, and means at the position adapted to be associated individually with any one of said trunk lines for selectively signalling a particular party on a
20 line connected thereto.

31. In a telephone system, party lines, trunk lines terminating at an operator's position, automatic switches for extending connections from said party lines to said trunk lines, means at the position for further extending the connections, a selective signalling device, and means controlled by the operator for temporarily associating said device with any one of said trunk lines to signal a particular party on a calling line.
25

32. In a telephone system, a party line, a plurality of trunks terminating at an operator's position, subscriber controlled automatic switches for extending a connection from said line to the position via an idle one of said trunks, means at the position for maintaining the connection after the calling subscriber hangs up, a signalling device common to all of said trunks, and means controlled by the operator for associating said device with the trunk line engaged in said connection to selectively signal the particular subscriber who originated the connection.
40

45. In witness whereof, I hereunto subscribe my name.

THOMAS F. CROCKER.

In witness whereof, I hereunto subscribe my name this 11th day of December, A. D.
50 1930.

VICTOR S. THARP.
